C. Lindle and Co. his
attys.

UNITED STATES PATENT OFFICE.

WILLIAM J. KEEP, OF TROY, NEW YORK.

DESIGN FOR A FIRE-PLACE STOVE.

Specification forming part of Design No. 5,928, dated June 11, 1872.

To all whom it may concern:

Be it known that I, WM. J. KEEP, of Troy, in the county of Rensselaer and in the State of New York, have invented certain new and useful Improvements in Design for Fire-Place Heater; and do hereby declare that the following is a full, clear, and exact description thereof, reference being had to the accompanying drawing making a part of this specification, in which—

Figure 1 is a front elevation of my improved heater. Fig. 2 is a sectional plan view of the top plate of the same enlarged. Fig. 3 is a like view of a section of the inclosing arch or frame; and Fig. 4 is a plan view of a section of the inclined plate which connects the upper and the mica sections.

Letters of like name and kind refer to like parts in each of the figures.

The principal feature of my invention is the design for the heater, which consists, generally, in a base surmounted by a mica section composed of two rows of vertical windows, above which is a straight cylindrical section inclosed at its upper end by means of a projecting top plate, the whole framed by or within an arch, substantially as is shown in Fig. 1.

Another feature of my invention is the design for the top plate A, as distinguished by a central portion, a, containing a series of radial ribs, b, and inclosed by means of a beaded molding, c, beyond and outside of which are other rows of ornaments, d, e, f, and g, while at the extreme edge of said plate is a plain strip, h, which terminates in a plain molding, i, all of said features being shaped and relatively arranged so as to present substantially the appearance shown in Figs. 1 and 2.

Another part of my invention is the design for the vertical mica section, composed of two rows of doors, K, the upper of which rows is placed above the fire-pot, while the lower row is placed opposite the sides of the same, so as to have substantially the appearance shown in Fig. 1.

Another feature of my invention is the design for the ornamental projecting portions L, placed between and above and below the rows of mica doors, said projections being provided with suitable sunk ornaments l, and presenting the general appearance shown in Figs. 1 and 3.

Another feature of my invention is the design for the curved portion M above the upper mica doors and at the base of the upper section, said part M being composed of the plain and ornamented strips m, n, and o, which inclose a concave strip, p, containing letters, substantially as is shown in Figs. 1 and 5.

Another part of my invention is the design for the upper section Q, which consists in a series of checkered panels divided by vertical bars or bands, substantially as is shown in Fig. 1.

Another part of my invention is the design for the ornamental panels R, placed between the mica section and the inclosing frame, said panels being shaped so as to present substantially the appearance shown in Figs. 1 and 4.

Another feature of my invention is the design for the curved or scroll work S, placed above the panels R, and inclosing the space between the frame and the upper section Q, and presenting substantially the appearance shown in Fig. 1.

Another feature of my invention is the recessed portions of the frame of the mica section above and below the rows of doors for the purpose of throwing dark shadows, substantially as is seen in Fig. 1.

Another part of my invention is the design for the inclosing frame or arch T, as distinguished by the rows of ornaments t, u, v, and w, beyond and outside of which are the plain and curved strips x x', y y', and z, the whole presenting substantially the appearance shown in Figs. 1 and 5.

Having thus fully set forth the nature and merits of my invention, what I claim as new is—

1. The design for the fire-place heater, substantially as shown and described.
2. The design for the top plate, substantially as shown and described.
3. The design for the mica section, substantially as shown and described.
4. The design for the ornamental projecting portions above and below the rows of mica doors, substantially as shown and described.
5. The design for the curved portion between the upper and mica sections, substantially as shown and described.
6. The design for the upper section, substantially as shown and described.

7. The design for the ornamental panels placed at the sides of the mica section, substantially as shown and described.

8. The design for the ornamental scroll-work placed at the sides of the upper section, substantially as shown and described.

9. The design for the frame of the mica section above and below the mica doors, substantially as shown and described.

10. The design for the frame or arch inclos-

ing the heater, substantially as shown and described.

In testimony that I claim the foregoing I have hereunto set my hand this 11th day of March, 1872.

WILLIAM J. KEEP.
